UNITED STATES PATENT OFFICE.

CHARLES F. BLACK, OF DAYTON, OHIO, ASSIGNOR TO DAVID P. CLARK, OF DAYTON, OHIO.

TOY.

1,272,195.

Specification of Letters Patent.

Patented July 9, 1918.

Application filed February 2, 1918. Serial No. 215,172.

To all whom it may concern:

Be it known that I, CHARLES F. BLACK, a citizen of the United States, residing at Dayton, in the county of Montgomery and State of Ohio, have invented certain new and useful Improvements in Toys, of which the following is a specification, reference being had therein to the accompanying drawing.

10 This invention relates to toys, and more particularly to a toy having a movable part which can be operated by a suitable actuating device, and can be maintained in continuous movement by repeated operations of 15 said actuating device.

The invention is an improvement upon the toy shown and described in Patent No. 1,242,194, granted to J. E. Jewell on October 29, 1917, which patent is now owned 20 by David P. Clark, assignee of the present invention. In the toy of the patent the actuating device comprises a drum to which is connected a strip of elastic and about 25 which is wound a cord which serves to place the elastic under tension so that when the cord is released the elastic will operate the movable part of the toy.

The object of the present invention is to provide a toy of this kind which will be very 30 simple in its construction and operation, and which will have its parts of such a character and so arranged that the several parts can be easily made and assembled, and that neither the making of the parts nor the assembling of the device will require a high 35 degree of accuracy, thus enabling the toy to be manufactured at a low cost.

It is also an object of the invention to so construct the toy that it will be very durable 40 and will have no parts which will be easily broken, or disarranged, in the normal operation of the toy.

It is also an object of the invention to so construct the toy that the power will be applied 45 by the operator directly to the movable part without first storing the same in the spring, or other device.

In the accompanying drawings Figure 1 is a side elevation, partly in section, of a 50 toy embodying my invention; Fig. 2 is a sectional view taken on the line 2—2 of Fig. 1 showing the movable part of the toy in dotted lines; Fig. 3 is a perspective detail

view, partly broken away, of the actuating mechanism; Fig. 4 is a side elevation of a 55 slightly modified form of the toy; and Fig. 5 is a sectional view taken on the line 5—5 of Fig. 4.

In these drawings I have illustrated one embodiment of my invention and have 60 shown the same as comprising a part to be operated, or movable member, 1, which in the present instance is in the form of a rotatable platform having mounted thereon a 65 series of figures. This part to be operated is connected with, and in the present instance is rigidly secured to a shaft 2, which is journaled in a suitable supporting structure. In that form of the toy here shown the shaft and its operating devices are 70 mounted within a casing 3 which is preferably cylindrical in form and may be open at its upper end. The shaft is journaled at its upper end in a transverse bar 4 extending across the casing 3, and is journaled in its 75 lower end in a step bearing 5 secured to the bottom of the casing 3. The lower end of the shaft is tapered, as shown at 6, and rests upon a bearing plate 7 arranged beneath the step bearing 5. This construction 80 is such that the bearings in the parts 4 and 5 may be simply openings formed in the sheet metal, of which these parts are formed. The bearing plate 7 constitutes a thrust bearing which receives the weight of 85 the shaft and the end of the shaft is reduced to a very small diameter so that there will be very little friction between the shaft and its bearing, and that it will revolve very 90 freely. Loosely mounted upon the shaft is 95 a pinion 8 which is preferably connected with the shaft by means of an overrunning clutch which will cause the shaft to rotate with the pinion when the latter is rotated in one direction, but will permit the pinion to rotate in the opposite direction independently of the shaft. In that form of the device here illustrated this clutch comprises a ratchet wheel 9 rigidly secured to the pinion and having its teeth extending upwardly 100 from the edges thereof so that they extend lengthwise of the shaft. A suitable pawl is mounted on the shaft to coöperate with the ratchet wheel, this pawl being so arranged that when the ratchet wheel moves 105 in one direction the teeth will engage the

pawl and cause the same to rotate therewith, and when the ratchet wheel rotates in the opposite direction the teeth thereof will elevate the pawl and move past the same. As here shown the pawl comprises a cross arm 10 mounted on the shaft and extending transversely of the ratchet wheel 9, its two end portions being arranged to engage the teeth on the opposite sides of the ratchet wheel. This pawl, or cross arm, is so connected with the shaft 2 that the shaft will rotate therewith, but the cross arm will be capable of vertical movement relatively to the shaft to permit it to ride over the teeth of the ratchet wheel. This may be accomplished in various ways, but for ease of manufacture and positive operation I have formed the connection by means of a plate 11, which is rigidly secured to the shaft 2 above the cross arm 10, and is provided on its opposite sides with depending lugs 12 spaced apart to receive between them the respective ends of the cross arm. Thus any rotatory movement imparted to the cross arm will be transmitted through the plate 11 to the shaft 2, but the cross arm is free to move vertically relatively to the plate. The plate 11 may be secured to the shaft 2 in any suitable manner, as by soldering. The pinion 8 is actuated by means of a toothed rack 13 which is here shown as segmental in shape and is mounted on a shaft 14 journaled at its upper end in a bearing in the cross bar 4, and at its lower end in a step bearing 15 secured to the bottom of the casing 3. Rigidly secured to the segmental rack and projecting beyond the shaft 14 is an actuating member, or thumb piece, 16, which extends through a slot 17 in the side wall of the casing, and is adapted to be engaged and operated by the thumb of the operator. If desired a finger piece 18 may be secured to the casing 3 at one end of the slot so that it may be grasped by the finger of the operator while the thumb engages the thumb piece 16. Thus it will be apparent that the movement of the segment about its axis by means of the actuating member 16 will cause the same to rotate the pinion 8 in a direction to actuate the shaft 2 and the movable part 1 of the toy. The momentum thus imparted to the movable part 1 of the toy will be sufficient to cause the same to continue to rotate for a considerable period after the movement of the toothed rack, or segment, 13, has been completed. After the completion of its movement the rack may be returned to its normal position either manually, or automatically. As here shown a spring 19 is connected with the segment and with the wall of the casing and serves to automatically return the same when the actuating member 16 is released. It will be noted that when the segment is in its normal

position the teeth thereof are out of mesh with the teeth of the pinion 8 and this pinion is therefore permitted to rotate with the shaft, thus not only eliminating the friction due to the rotation of the shaft within the pinion and the movement of the pawl 10 over the ratchet teeth, but also eliminating the noise incident to the movement of the pawl over the ratchet teeth. In the present device a stop 20 is provided to limit the movement of the pinion in its operative direction, but obviously the movement of the segment may be controlled in any desired manner.

While I prefer that the power should be applied directly to the mechanism by the operator, in the manner above described, this same mechanism may, if desired, be used for first storing the power in a spring and then applying it to the operating mechanism by means of the spring. To accomplish this there will be no change in the mechanism itself, but a spring 21 will be so connected with the segment 13 as to move the same in its operative direction, as shown in Fig. 5. This spring will serve to normally retain the segment and consequently the actuating member 16 in positions opposite those shown in Fig. 2, and to operate the device the segment is first retracted against the tension of the spring in a direction to cause the ratchet wheel to ride over its pawl and then released to permit the spring to move the same in a direction to actuate the pinion and the shaft. In this construction a finger piece 22 is arranged at that end of the slot in the casing opposite the normal position of the operating member, or finger piece, 16.

The operation of the device will be readily understood from the foregoing description thereof and it will be apparent that a single operation of the segment will cause the movable part of the toy to be rotated at a high speed and to thus attain a very considerable momentum which will cause it to continue its movement for a long period after the segment has been returned to its normal position. Because of the character of the bearings and the small amount of friction on the shaft 2 the movable part will continue to rotate for a relatively long period, and by repeating the operation of the segment at intervals the movable part can be caused to rotate continuously as long as desired.

It will be noted that not only is the construction of the mechanism such as to subject the shaft carrying the movable part to have little friction, but that the several parts are such that they can be very easily made from sheet metal, and that there are no close fits between the parts, or fine adjustments which require accurate work. Consequently the device can be made by ordinary labor

without any liability of its being inoperative when completed because of inaccuracies in manufacturing, or assembling the same.

While I have shown and described one embodiment of my invention I wish it to be understood that I do not desire to be limited to the details of construction as various modifications will occur to a person skilled in the art.

Having now fully described my invention, what I claim as new and desire to secure by Letters Patent, is:—

1. In a toy a vertically arranged shaft, a part to be operated connected with said shaft, a pinion loosely mounted on said shaft, a toothed wheel rigidly secured to said pinion, a member mounted on said shaft for vertical movement relatively thereto, said member being held against rotation relatively to said shaft and having a part cooperating with said toothed wheel to establish a connection between said pinion and said shaft, said part and the teeth of said wheel being so arranged that when 25 said pinion rotates in one direction said part will operatively engage one of said teeth, and when said pinion rotates in the other direction said member will be moved lengthwise of said shaft to permit said part 30 to ride over said teeth, and a toothed rack to actuate said pinion.

2. In a toy, a part to be operated, a shaft connected with said part, a pinion loosely mounted on said shaft, a ratchet wheel rigidly secured to said pinion and having its teeth extending lengthwise of said shaft, a part mounted on said shaft for vertical movement relatively thereto and held against rotation relatively thereto, said part being 40 arranged to engage the teeth of said ratchet wheel to connect the same with said shaft, a toothed rack arranged to mesh with said pinion, and a finger piece connected with said rack to actuate the same.

45 3. In a toy, a part to be operated, a shaft connected with said part, a pinion loosely mounted on said shaft, a ratchet wheel rigidly secured to said pinion and having upwardly extending teeth, a cross arm loosely mounted on said shaft above said ratchet wheel and extending transversely to the latter, a plate rigidly secured to said shaft and having depending lugs arranged to embrace said cross arm and cause said shaft to rotate therewith, and to permit said cross arm to move lengthwise of said shaft independently thereof, a toothed rack arranged to mesh with said pinion, and means to actuate said rack.

60 4. In a toy, a part to be operated, a shaft connected with said part, a pinion loosely mounted on said shaft, an overrunning clutch connection between said pinion and said shaft, a toothed rack arranged to actu-

ate said pinion, a finger piece to move said rack in one direction, and a spring to move said rack in the opposite direction.

5. In a toy, a casing, a shaft mounted on said casing, a part to be operated arranged beyond said casing and connected with said shaft, a pinion loosely mounted on said shaft, an overrunning clutch connection between said pinion and said shaft, a toothed segment pivotally mounted within said casing and arranged to mesh with said pinion, and a finger piece connected within said segment and extending beyond said casing.

6. In a toy, a casing, a shaft mounted on said casing, a part to be operated arranged beyond said casing and connected with said shaft, a pinion loosely mounted on said shaft, an overrunning clutch connection between said pinion and said shaft, a toothed segment pivotally mounted within said casing and arranged to mesh with said pinion, a finger piece connected with said segment and extending beyond said casing to move said segment in one direction, and a spring to move said segment in the other direction.

7. In a toy, a casing, a shaft mounted in said casing, a part to be operated arranged beyond said casing and connected with said shaft, a pinion loosely mounted on said shaft, an overrunning clutch connection between said pinion and said shaft, a toothed segment pivotally mounted in said casing and arranged to mesh with said pinion, manually operated means for moving said segment in a direction to actuate said movable part of said toy, and means to automatically return said segment to its normal position.

8. In a toy, a casing, a shaft mounted in said casing, a part to be operated arranged beyond said casing and connected with said shaft, a pinion loosely mounted on said shaft, an overrunning clutch connection between said pinion and said shaft, a toothed segment pivotally mounted in said casing and arranged to mesh with said pinion, means to move said segment in a direction to actuate said operable part of said toy and return the same to its normal position, said segment being so arranged with relation to said pinion that when the segment is in its normal position its teeth will be out of engagement with said pinion.

9. In a toy, a casing, a cross bar mounted in said casing near the top thereof, a bearing supported within said casing near the bottom thereof, a shaft loosely mounted in said bearing and having its lower end supported on the bottom of said casing, a part to be operated connected with said shaft, a pinion loosely mounted on said shaft, a clutch connection between said pinion and said shaft, a toothed rack arranged to en-

gage said pinion, and means to actuate said rack.

10. In a toy, a casing, a cross bar mounted in said casing and having an opening therein, a step bearing mounted in said casing in alinement with the opening in said cross bar, a bearing plate arranged beneath said step bearing, a shaft extending through said opening and said step bearing, and having a 10 tapered lower end resting upon said bearing

plate, a pinion loosely mounted on said shaft, an overrunning clutch connection between said pinion and said shaft, a toothed rack to actuate said pinion, manually operated means for actuating said rack, and a part 15 to be operated connected with said shaft.

In testimony whereof, I affix my signature hereto.

CHARLES F. BLACK.
